UNITED STATES PATENT OFFICE.

JOHN W. SELF, OF BOWLING GREEN, KENTUCKY.

COMBINED SEED-SOWER AND CLOD-CRUSHER.

SPECIFICATION forming part of Letters Patent No. 409,070, dated August 13, 1889.

Application filed March 30, 1889. Serial No. 305,367. (No model.)

To all whom it may concern:

Be it known that I, JOHN W. SELF, a citizen of the United States, residing at Bowling Green, in the county of Warren and State of Kentucky, have invented a new and useful Combined Drill, Clod-Crusher, &c., of which the following is a specification.

My invention relates to an improvement in combined drills, clod-cutters, harrows, rollers, and rakes; and it consists in the peculiar construction and combination of devices that will be more fully set forth hereinafter, and particularly pointed out in the claims.

In the accompanying drawings, Figure 1 is a side elevation of my improved machine, showing all the attachments in position thereon. Fig. 2 is a top plan view of the same. Fig. 3 is a vertical longitudinal sectional view of the same. Fig. 4 is a detail sectional view of the seed-hopper.

The main frame A is rectangular in form, and comprises a pair of longitudinal side bars B, cross-bars C D, which connect the front and rear end thereof, a cross-bar E, which connects the said bars B at a suitable distance in rear of the bar C, and a longitudinal central bar F, which connects the bars E D. An axle G is arranged transversely under the frame, and is secured to the bars B at a point slightly in rear of the cross-bar E. On the spindles of the axle are journaled a pair of supporting-wheels H. The tongue I has its rear end mortised to the center of the axle, and the said tongue is secured under the center of the cross-bar C by means of a bolt K. The seat L for the driver is supported by a spring-bar M, which has its lower end bolted to the cross-bar E near the center of the latter.

The clod-cutter comprises a rectangular open frame N and a series of rearwardly-inclined cutting teeth or knives O, which are attached to and depend from the front and rear bars of the said frame. On the sides of the frame are bolted plates P, which are provided at their rear ends with vertical arms R, having vertical slots S. The said arms extend between and bear against the inner sides of the longitudinal side bars B, and the slots in the said arms are engaged by studs or pins T, which project inward from said side bars, and thereby the rear side of the

frame is adapted to be raised and lowered, as will be readily understood.

A link U, which is arranged substantially in the form of a hook, is connected to and depends from the tongue near the rear end of the latter, and the said hook-ring engages a keeper V on the center of the front bar of the clod-cutter frame and serves to support the same. A rod W is attached to the rear side of the clod-cutter frame, extends upward to within convenient reach of the driver, and enables him to raise and lower the clod-cutter frame as may be desired. Arranged under the main frame and in rear of the clod-cutter is a harrow-frame X, which is of substantially the same size and shape as the clod-cutter frame, and is provided with harrow-teeth which depend from the front and rear bars thereof. Pivoted to the front corners of the said harrow-frame is a bail Z, from the center of which projects a forward-extending hooked arm A', which engages a loop or keeper B' on the rear side of the axle at the center thereof. A pair of link-rods C' are pivoted to the inner sides of the bars B and depend therefrom, and the lower ends of the said link-rods are pivoted on the ends of a rod D', which also serves to secure the yoke to the harrow-frame. A hand-lever E' is pivoted to the side of the bar F, near the rear end thereof, and is connected to the rear side of a harrow-frame by a link-rod G', and thereby the said harrow-frame is adapted to be raised and lowered, as will be readily understood.

A pair of bracket-arms H' are secured to the rear corners of the main frame and project rearward therefrom, the said bracket-arms being bolted or otherwise detachably secured on the said frame, and between the said arms is pivoted the cross bar or head I' of a rake K'. The tines or teeth of the rake are attached to the said cross bar or head and are curved downward and rearward therefrom, as shown, and the rake-head is connected to the hand-lever E' by a link-rod L', and thereby the rake-teeth may be lowered to and raised from the ground by operating the hand-lever.

Pivoted to the outer sides of the bars B, at the rear ends thereof, are a pair of rearward-extending link-arms M', between the rear

ends of which is journaled a roller N', which may be made either of wood or metal. The said roller travels in rear of the harrow and serves to level the ground and pulverize the 5 same.

The seed-hopper O', which is rectangular in shape, is adapted to be inserted in the rectangular space a, inclosed by the beams B and by the cross-bars C E, the lower edges of the 10 side walls of said hopper bearing on the tongue. The bottom of the hopper is inclined, as shown, and is provided with a series of discharge-openings P', arranged near its lower edge. A slide R' is arranged on the bottom of 15 the seed-hopper, and is provided with openings S', which are of the same diameter as the openings P', and are adapted to register therewith, and the said slide projects beyond the ends of the hopper. One of the projecting 20 ends of the slide is provided on its rear side with a series of three notches 1 2 3, and a detent-lever 4 is pivoted to the proximate end of the hopper and is adapted to engage either of the said notches. When said detent-lever is 25 engaged with the notch 3, the openings S' are directly over the openings P', and the latter are opened to their full extent, so that a maximum quantity of seeds will be discharged from the hopper. When the said slide is 30 moved outward and the detent-lever is caused to engage the notch 2, the openings P' will be about half covered, and consequently a less quantity of seeds will be sown on a given area, and when the said lever engages the 35 notch 1 the openings P' are entirely closed. The cover T' of the hopper is provided with the hinges U', whereby it can be readily opened or closed. When the hopper is charged with seed and the openings P' are uncovered 40 to the desired extent, the seeds will be dropped from the said hopper onto the ground and will be harrowed into the soil by the harrow, and the roller which follows the harrow will serve to cover the seeds and to press the soil

firmly above them, and thereby promote their 45 ready germination.

The motion of the machine over the ground will usually be found sufficient to cause the seeds to be discharged; but suitable stirring mechanism may be employed, if thought ad- 50 visable.

Having described my invention, I claim—

1. The frame mounted on the axle and having the side bars B and the parallel cross-bars C E, and the tongue with its rear end 55 under the centers of said cross-bars, in combination with a detachable hopper rectangular in form and adapted to be placed on the rear end of the tongue and arranged between the bars B and the cross-bars C E, substantially 60 as described.

2. The combination, with the frame A, having the pins or studs T, of the clod-cutter, the hook-link connecting the front end thereof to the frame, the vertical arms R, having the 65 vertical slots S, engaging the pins or studs T, and the lever or rod to raise and lower the rear end of the said frame, substantially as described.

3. The combination, with the frame A, having 70 the keeper B', of the harrow-frame having the bail at its front end provided with the hook-arm to engage said keeper, the link-arm C', pivotally connected to and depending from the frame A, and having their lower end pivotally connected to the sides of the harrow-frame near the front side of the latter, the hand-lever pivoted on the frame, and the rod connecting the same to the rear side of the 75 harrow-frame, substantially as described. 80

In testimony that I claim the foregoing as my own I have hereto affixed my signature in presence of two witnesses.

JOHN W. SELF.
